[57] CLAIM

The ornamental design for a "tool Handle", as shown and described.

DESCRIPTION

FIG. 1 is a front perspective view of a tool handle showing our new design;

FIG. 2 is a rear elevation of FIG. 1;

FIG. 3 is a top plan view of FIG. 1; and,

FIG. 4 is a bottom plan view of FIG. 1.

The fragmentary tool shaft depicted by means of broken lines in FIGS. 1 and 2 has been shown for illustrative purposes only and forms no part of the claimed design.
